UNITED STATES PATENT OFFICE

THOMAS F. CROCKER, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed September 26, 1927, Serial No. 221,878. Renewed December 12, 1929.

The present invention relates to telephone systems in general, but is concerned more particularly with cord circuits and trunk circuits used in giving toll service to the subscribers of an automatic telephone exchange.

5 This invention is an improvement on my prior application Serial No. 161,514, filed January 17, 1927, particularly with reference to the feature in the prior application involving the arrangement whereby the dialling 10 keys and other keys are common to all the cord circuits of an operator's position.

One object of the invention is the production of suitable apparatus whereby the 15 amount of work performed by the operator is reduced. This is accomplished by removing the cord-splitting contacts from the dial keys and placing them on suitably-controlled relays. In this way, one or the other of the 20 two dial keys may be left thrown all the time, with the result that the proper cord-splitting relay operates at the proper time to cause the impulses from the operator's dial to be transmitted over the end of her cord circuit indicated by which of the two dialling keys 25 is left operated.

In this connection, a saving of contacts and a simplification of the circuits result, because the same cord splitting relays above mentioned for use in connection with dialling 30 may be used to perform the cord-splitting operation necessary during coin collect and refund and such other operations as may require a splitting of the cord.

It is a further object to prevent the operator 35 from hearing severe clicks when she plugs into a trunk line with her talking key thrown, as she may often do when she is inserting the calling plug of a cord into a trunk 40 line jack after she has answered a call with the answering plug. This object is obtained by providing a short-circuiting relay to short circuit the receiver of the operator under the control of the sleeve conductor of the cord, the 45 arrangement being such that the sleeve of the plug contacts with the sleeve of the jack and causes her receiver to be short circuited before the tip and ring contacts of the plug and jack have been brought together.

50 A feature of the present arrangement in

connection with the operator's headset is that the operator's receiver is maintained short circuited by relays controlled by off-normal contacts of the calling device for an interval following the operation of the calling device in 55 order to permit a selector, operated by the train of impulses just sent out, to complete its hunting operation and switch through so as to avoid disagreeable clicks in the operator's receiver when the switching through operation is performed.

A further object is the production of a new and improved trunk circuit for use in connection with a toll service trunk over which the current flow is reversed upon the completion 65 of the connection to the called line and is discontinued during conversation. One feature of the improvement is that the trunk circuit does not operate to indicate unanswered supervision to the operator until the current 70 reversal has taken place, and the other feature is that the action of the sleeve relay occurring after the reversal has taken place results in the closure of an alternate holding 75 circuit during the ringing operation, whereas the holding circuit is not closed by the same action of the sleeve relay during dialling.

Another object of the invention is the production of novel circuit arrangements in connection with the operator's cord circuit for timing a conversation and warning the operator when the subscribers have conversed for a predetermined length of time, three minutes, for example. In the specific embodiment of the invention herein disclosed and described, the operator is provided with a starting pushbutton (common to her several cord circuits) which she operates when the conversation begins. A slow-acting device, 80 timed to operate at the end of the predetermined interval, operates to signal the operator at the end of such interval.

It is a further object of the invention to 85 simplify the operator's cord circuits by causing the calling supervisory lamp to flash when the conversation has proceeded for the predetermined interval, rather than using a separate lamp.

90 There are other objects and features of the 100

invention, having to do for the most part with the circuit details involved in carrying out the foregoing.

The various objects and features of the invention will be understood best upon a further perusal of the description in connection with the accompanying drawings, comprising Figs. 1 and 2, showing by means of the usual circuit diagrams so much of the apparatus in a telephone system embodying the features of the invention as is necessary to an understanding of the same.

In the accompanying drawings, Fig. 1 shows a cord circuit at a toll-operator's switchboard together with a jack-ending toll line at the left and a toll service trunk at the right. The toll line may be one extending to a distant city. The toll service trunk is a trunk line leading to a toll service trunking system such as, for example, the one shown in the Wicks Patent #1,633,149, granted June 21, 1927.

Fig. 2 shows the position equipment, common to all the cords of the switchboard, including the various keys and relays and the operator's headset.

The invention having been described generally, a detailed description of the operation of the apparatus shown will now be given. For this purpose it will be assumed that the operator receives a call over the toll line, Fig. 1, for a subscriber whose line terminates in the local exchange.

In response to the ringing current transmitted over the toll line from the distant end thereat line relay 101 is operated and closes a locking circuit for its lower winding through contacts of cut-off relay 102, at the same time closing a circuit for the call lamp 103. The operator, upon noting the lighted condition of the call lamp, inserts the answering plug of an idle cord circuit, for example the one shown in the drawings, into the jack J^1 . When the plug P^1 enters the jack J^1 , cut-off relay 102 is energized through the sleeve of the plug and jack and removes the line relay from in bridge of the talking conductors of the jack, at the same time unlocking the line relay so as to extinguish the call lamp 103.

The circuit of relay 102 at this time includes contacts of the ringing key, contacts of the talking key, contacts of relays 107 and 106 and the supervisory lamp 103 and resistance 104 in parallel. The lamp 103 however is not lighted owing to the relatively high resistance of relay 102.

Having inserted the plug P^1 into the jack J^1 , the operator operates her talking key in the cord circuit so as to be able to converse with the calling operator. When the talking key is thrown, it connects the tip and ring conductors of the answering plug to the common conductors 131 and 132 leading to the position equipment shown in Fig. 2, and it

disconnects the sleeve of the plug P^1 from the associated equipment in the cord circuit and extends it over conductor 133 to the holding circuit including resistance 202 Fig. 2, and contacts on certain of the common keys. The tip and ring strands of the plug P^1 having been connected over conductors 131 and 132 and through contacts of the cord splitting relay 201 to the tip and ring conductors with the calling operator and ascertain the destination of the call.

As a further result of the operation of the talking key, relay 108, Fig. 1, is operated and it divides the cord into two sections, connecting the tip and ring strands of the calling plug P^2 over conductors 134 and 135 to the position equipment shown in Fig. 2. Relay 108 also disconnects the sleeve of the plug P^2 from the associated supervisory lamp 112 and, assuming the dial call key to be normal, connects it over conductor 136 to the common holding resistance 203, Fig. 2, through contacts of certain of the common keys. However, if the operator has the dial call key operated, and she usually has, the sleeve conductor 136 of the common apparatus is extended through contacts of the dial call key, contacts of the off-normal relay 209, associated with the calling device CD, and contacts of relay 205 to the upper winding of relay 207 for a purpose which will appear presently.

Having ascertained the number of the desired subscriber, the operator inserts the plug P^2 of the cord circuit into the jack of an idle toll-service trunk, the jack J^2 for example. As the plug is inserted into the jack, the tip of the plug makes contact with the tip of the jack before the ring of the plug makes contact with the ring of the jack, due to the usual plug and jack construction, whereupon the upper spring contacts of the jack are closed by the associated tip springs, grounding the upper terminal of sleeve relay 115. This ground potential is transmitted through relay 115 and the sleeve of the jack to the sleeve of the plug, causing the quick acting relay 207 Fig. 2 to energize over the sleeve circuit and through the contacts above-mentioned, to short circuit the operator's telephone. It has been found by test that this short circuiting operation is completed before the ring contact of the plug makes contact with the ring spring of the jack, preventing a click in the operator's headset from the battery potential across the tip and ring contacts of the jack.

Sleeve relay 115 of the trunk line energizes at this time and closes a bridge across conductors 120 and 121 through the lower winding of relay 116 and the winding of relay 119. Relay 119 energizes through the line relay (not shown) of the switch to which the toll-service trunk extends, but the electro-polarized relay 116 does not operate at this

time owing to the fact that the current flow in its two windings is in opposite directions. It will be noted that the resistance 117 in series with the upper winding of the relay limits the current flow therethrough to a value about equal to the line current in the trunk. Upon energizing, relay 119 closes a parallel holding circuit across conductors 120 and 121 through the resistance 118, at the same time removing the shunt from around the associated condensers. These condensers, it may be pointed out, are of a sufficient capacity to permit ringing tones and busy tones to be heard by the operator, but they prevent the starting of the ringing operation in the toll service trunking systems due to stray ringing currents. Relay 119 remains operated by current flow through it in multiple with the holding resistance 118.

Referring now to the operator's headset shown in Fig. 2, as a further result of the above mentioned energization of relay 207 over the sleeve circuit of the plug P^2 , Fig. 1, a circuit is closed for the slow-acting relay 206. Relay 206 thereupon operates and closes a multiple shunt around the operator's receiver in addition to closing a circuit for relay 205 through the resistance 208. Relay 208 operates and locks itself to the sleeve extended conductor, at the same time joining the two terminals of the lower winding of relays 207 together and opening the circuit through the upper winding of the relay. Relay 207, being quick to pull up initially, as above pointed out, is now slow to fall back due to the closed lower winding. After an interval, relay 207 falls back and opens the circuit of relay 206, whereupon relay 206 falls back a moment later and removes the shunt from around the operator's telephone, at the same time opening the initial circuit of the now-locked relay 205. The resistance 208 is included in the initial operating circuit of the relay 205 so as to avoid shunting the sleeve relay 115 in the toll service trunk Fig. 1.

By the time the relays 205-207 have gone through the above cycle of operation the current flow in conductors 120 and 121, Fig. 1, has become steady and the condensers associated with relay 119 have been inserted in the talking circuit so that no click is produced when the shunt is removed from around the operator's telephone.

Having inserted the plug P^2 into the jack J^2 with the above described results, the operator, who, as above mentioned, is assumed to have left the dial call key Fig. 2 operated from the previous operation, now turns her calling device CD in accordance with the various digits in the desired number.

When the calling device CD is moved from its normal position, the off-normal springs 231, 232, and 233 all make contact with each other. When the contact is made between

springs 232 and 233, a circuit is closed through relay 209 and contacts of the operated dial call key for the cut-off relay 201, whereupon relay 201 responds and disconnects conductors 131 and 132 from the operator's headset conductors. When springs 232 and 231 make contact, the ground potential from spring 233 is extended to the upper winding of relay 207, whereupon relay 207 operates, followed by the operation of relay 206. With these two relays operated, the operator's telephone is short circuited, as is associated condenser in the talking circuits. Relay 209 operates in series with the cut-off relay 201 and opens the extended sleeve circuit, permitting the sleeve relay 115 in the toll service trunk Fig. 1 to fall back. Relay 205 Fig. 2, remains operated, due to the circuit closed for it through resistance 208 by relay 206. When relay 115 falls back, it opens the circuit through the lower winding of relay 116 and the winding of relay 119, whereupon relay 119 falls back and short circuits the associated condensers, at the same time removing the bridge including resistance 118 from across conductors 120 and 121. The current flow formerly existing through these two bridges now takes place over the tip and ring springs of the jack and the corresponding contacts of the plug through the extended tip and ring conductors 134 and 135 and through the operator's headset by way of contacts on cut-off relay 204, the condenser associated with the operator's headset being short circuited by contacts of the operated relay 206. The path of this current flow it will be noted is through the impulse springs of the calling device CD .

As the dial of the calling device rotates back to its normal position, after having been released, the circuit is interrupted the necessary number of times at the impulse springs of the calling device so as to bring about the desired operation of the first switch in the toll service train.

When the calling device CD reaches its normal position, the off-normal springs 231-233 separates, whereupon relay 209 falls back, but the slow acting relay 201 remains operated for a slight interval so as to permit a more stable condition to be reestablished in the common circuits before conductors 131 and 132 are reconnected. When relay 209 falls back, it replaces battery through relay 205, now locked up through resistance 208 by relay 206, on the extended sleeve circuit, energizing sleeve relay 115 Fig. 1 in the toll service trunk. Relay 115 operates again and recloses the local holding bridge across conductors 120 and 121 through relay 119 and the lower winding of relay 116. Relay 119 now energizes in multiple with the loop through the operator's headset and the calling device CD , Fig. 2, and closes the local multiple bridge through resistance 118, at the same

time reinserting the associated condensers into the talking circuit.

In the operator's circuit, Fig. 2, the circuit of the upper winding of relay 207 is opened by the off-normal springs 231 and 232 when the calling device CD reaches its normal position, with the result that relay 207 falls back after an interval, being rendered slow-acting by the closed circuit through its lower winding. Upon falling back, relay 207 opens the circuit of the slow acting relay 206, with the result that relay 206 falls back after an interval and removes the shunt from around the associated condenser in the talking circuit, at the same time opening the local locking circuit for relay 205 and removing the shunt from around the operator's telephone. The circuit having become stabilized in the meantime, with no current flow in the operator's circuit, no click is heard. Relay 205 remains locked up over the extended sleeve circuit.

The operator now dials the remaining digits in the desired number.

If the called line is busy, the busy tone is heard by the operator after the complete number is dialled, and she may release the connection by withdrawing the plug P^2 from the jack J^2 .

Assuming that the called line is idle, the connector in use seizes the called line and initiates operations which result in a reversal of the current flow in conductors 120 and 121. This takes place after relays 115 and 119, of the trunk have reoperated, but before the operator's relays 207 and 206 have fallen back. When this reversal occurs, relay 116 operates as the current flows in its windings now assist each other, and relay 119 falls back momentarily owing to the fact that the magnetism in its magnetic circuit must die down to zero and build up again in the opposite direction when the current flow is reversed. If it were not for the presence of the bridge including resistance 118 across the trunks through contacts of relay 119, the line relay supplying current to conductors 120 and 121 would fall back at this time due to the high impedance of relay 119. However, resistance 118 affords a ready path for the reversed current flow over which the line relay is held until relay 119 lets go. When relay 119 lets go, the associated condensers are short circuited and the current flow over conductors 120 and 121 is continued through the operator's circuit (the condenser and the operator's telephone being still short circuited by relay 206 Fig. 2). The current flow through resistance 118 is picked up again when relay 119 energizes in the opposite direction.

As a result of the energization of the electro-polarized relay 116, a ground-return holding circuit is prepared at the lower armature of the relay, and a shunt is placed

around the upper winding of sleeve relay 115 at the upper contacts of the electro-polarized relay through contacts of relay 119, thereby permitting an increased current flow over the sleeve circuit so as to light the supervisory lamp 112 when the operator restores the talking key.

Having dialled the number and not having received the busy signal, the operator now restores her talking key, whereupon relay 108 falls back completely disassociating the cord circuit from the position equipment. The sleeve circuit of the plug P^2 is now transferred back to the supervisory lamp 112 whereupon the lamp 112 becomes lighted over the sleeve circuit in series with the lower winding of the sleeve relay 115, the upper winding of this relay being now shunted by the relays 116 and 119. By the lighted condition of the lamp 112, the operator is informed that the called line is idle and has been seized.

In order to signal the subscriber on the called line, after she has been notified to do so by the calling operator, the operator throws the ringing key associated with a plug P^2 , whereupon ringing current is transmitted over the tip and ring conductors of the jack J^2 . At the same time, the shunt is removed from around the resistance 114 by the ringing key, extinguishing the lamp 112 and causing the sleeve relay 115 to fall back. The resistance 114 must not be so high as to cause the deenergization of a tool-line sleeve relay such as 102 associated with the jack J^1 . As a result, the resistance is high enough to cause the sleeve relay to fall back when its upper winding is shunted, but not otherwise. The upper winding of the relay is shunted at this time by the contacts of relays 116 and 119. When the sleeve relay falls back, it grounds the lower conductor 121 through contacts of relay 116, at the same time opening the bridge through the lower winding of relay 116 and relay 119. Relay 116 remains operated by the current flow through its upper winding alone. Relay 119 however, falls back, shunts the associated condensers, and would remove the shunt from around the upper winding of relay 115 were it not for the upper contacts of relay 115 which closes a multiple point in its own shunt circuit. The ringing current now passes out over the upper conductor 120 to the switch train and causes the automatic signalling of the called subscriber to start in a manner explained in the Wicks patent hereinbefore referred to.

When the operator restores the ringing key, the ringing current is removed and the resistance 114 is short circuited. When this occurs, the supervisory lamp 112 is again lighted, and relay 115 again pulls up. The ground potential placed on conductor 121 during the time that relay 115 is deenergized with relay 116 operated is effective in main-

taining operated the line relay which has a winding connected between battery and conductor 121 at this time.

When the called subscriber responds, the talking circuit is closed in the switch train and the current flow over conductors 120 and 121 is stopped, the so-called dry trunk supervision being used. When this occurs, relay 119 falls back and short circuits the associated condensers in the talking circuit so as to afford a better talking condition and removes the bridge through resistance 118 from across the talking circuit. At the same time, relay 119 removes the shunt from around the upper winding of relay 116, thereby extinguishing the supervisory lamp 112, which does not remain lighted in series with the entire winding of the sleeve relay.

The calling and called subscribers may now converse with each other in the usual manner.

When the conversation is over, the called subscriber replaces his receiver whereupon the current flow in conductors 120 and 121 is resumed, operating relay 119 to again replace the shunt around the upper winding of the sleeve relay, giving a disconnect signal.

The distant operator may send a disconnect-application of ringing current over the toll line, in which case relay 107 of the cord circuit operates and removes the shunt from around relay 106, whereupon relay 106 operates and opens a further point in its shunt circuit, at the same time closing a circuit for the lamp 103, which lamp becomes lighted as a disconnect signal.

When the operator pulls down the connection, the cord-circuit apparatus reverts to its normal position, and the toll service switch train is released.

Assuming now that the operator desires to collect a coin deposited at a pay station called over the cord circuit shown in the drawings and over the toll-service trunk shown, she operates her collect call key with the talking key thrown in the cord. This of course takes place after the connection has been set up to the line, in which case the electro-polarized relay 116 is operated. When the collect call key is thrown, the lower contacts of the key operate relay 204 which splits the cord and places the current from the negative 110 volt source on the extended tip conductor 134. The operated key also removes battery from the extended sleeve conductor 136, deenergizing sleeve relay 115. Sleeve relay 115 opens the circuit through relay 119, deenergizing this relay so as to shunt the condensers and permit the high voltage current to pass over the upper conductor 120. Relay 115 also closes a ground return circuit at its lower contact to conductor 121 so as to afford a return path for the high voltage

train and to afford a holding circuit for the automatic switches. When the key is restored, the circuits shown return to their previous condition.

In the same way, the operator may refund a coin, by operating the refund call key.

In case the operator desires to converse over the answering end of the cord while the calling end is cut off, she operates the cut-off call key, operating relay 204 to cut off the calling end, leaving her headset connected to the answering end of the cord.

It will be noted that the keys above referred to appear in duplicate on both ends of the common equipment so that either end of the cord may be used in effecting a connection. It is to be noted especially that the end of the cord over which dialling impulses are transmitted is dependent entirely upon which of the two dial keys is thrown when the dial moves from its normal position. If the dial call key is thrown as hereinbefore described, the answering cut-off relay 201 is operated as hereinbefore pointed out, but if the dial answer key is thrown instead, the calling cut-off relay 204 is operated instead, and the dial pulses are transmitted over the answering end of the cord.

Assuming now that the operator wishes to time a connection and to be notified when a conversation has proceeded for a predetermined length of time, for example, three minutes, she operates the common push button PB, Fig. 1, while the talking key and corresponding relay 108 of the cord circuit

over which the conversation is passing are operated. When this occurs, a circuit is closed for the starting relay 111, whereupon this relay operates and locks itself to the sleeve conductor in multiple with the supervisory lamp, at the same time opening its initial circuit and preparing a circuit for the retarded relay 109, which is completed when the talking key is restored. Relay 109 is retarded by a suitable slow-acting device, such as, for example, the dash pot 110. At the end of the predetermined interval, the slow-acting device 110 permits the contacts of relay 109 to close whereupon the supervisory lamp 112 commences to flash under the control of the flasher F.

The resistance associated with the flasher F in the flashing lead is to prevent the short circuiting of the sleeve relay associated with the jack into which the plug P² is inserted.

Upon noting the flashing condition of the supervisory lamp 112, the operator re-operates her talking key and may warn the subscribers that they have conversed the predetermined interval or takes such other steps as she may be instructed to take.

When the operator throws her talking key the starting relay 111 remains operated, but relay 109 is thereupon released to stop the flashing operation. If the subscribers have

a desire to converse for another period of time, the operator merely restores her talking key, whereupon the timing operation commences again.

What is claimed is:

- 5 1. In a telephone system, a trunk line including two talking conductors, a bridge across said talking conductors, a relay energized responsive to current flow through said bridge, a second bridge, a condenser connected in series with one talking conductor and directly shunted when said relay is normal, and contacts on said relay effective when the relay is operated to remove the shunt from around said condenser and to place said second bridge directly in multiple with the first. 70
- 10 15 2. In a telephone system, a trunk line including two talking conductors, a condenser in series with one of said talking conductors, a bridge across said talking conductors on one side of said condenser, a relay in said bridge responsive to current flow over said trunk line, a shunt around said condenser controlled by said relay, a second bridge across said trunk line in multiple with the first bridge when the relay is operated, and contacts on said relay for opening the second bridge and for shunting said condenser when the relay falls back responsive to a cessation 80
- 20 25 30 35 40 45 50 55 60 65 70 75 80 85 90 95 100 105 110 115 120 125 130
3. In a telephone system, a trunk line comprising two talking conductors outgoing from a switchboard, a condenser inserted in one of said talking conductors, a shunt normally around said condenser, a bridge across the conductors of said trunk line connected to the outgoing side of said condenser, a second bridge across said trunk line directly in multiple with the first bridge, means for placing a bridge across the trunk line on the switchboard side of said condenser and for opening the first named bridge, means responsive to the cessation of current flow in the first named bridge for shutting said condenser and for removing the second bridge from across the trunk line. 100
4. In a telephone system, a trunk line, three bridges arranged to be placed across said trunk line, means for placing the first bridge across the said trunk line, means responsive to the resulting current flow through the first bridge for placing the second bridge across the trunk line, means for preparing the third bridge and for opening the first bridge, means responsive to the resulting cessation of current flow in the first bridge for removing the second bridge from across the trunk line and for placing the third bridge across the trunk line. 110
5. In a telephone system, a trunk line, two bridges arranged to be placed across said trunk line, means for placing the first bridge across the trunk line, means for preparing the second bridge and for opening the first bridge, means responsive to the opening of the first bridge for placing the second bridge across said trunk line, and a third bridge controlled in accordance with the current flow in the first bridge for maintaining the current flow in said trunk line after the first bridge is opened and until the second bridge is placed across the trunk line. 120
6. In a telephone system, a trunk line extending from a manual switchboard to an automatic switchboard, means for extending a connection to said trunk line at said manual switchboard and for placing a switch holding bridge across the trunk line, said bridge excluding said manual switchboard, operator-controlled means for opening said holding bridge to permit the operation of the mechanism at the automatic switchboard to be controlled from the manual switchboard and for opening it subsequently to permit ringing current to be transmitted from the manual switchboard to the automatic switchboard, a device at said manual switchboard end of said trunk revertively controlled from the automatic switchboard after the automatic switching mechanism has been set and before the ringing current has been transmitted, and means controlled by said device for rendering effective an alternative holding circuit for the automatic switching mechanism when said bridge is opened to permit the passage of ringing current. 130
7. In a telephone system, a trunk line extending from a manual switchboard to an automatic switchboard, ringing-current-blocking condensers inserted in said trunk line, means controlled by the operator at said manual switchboard for shunting said condensers to permit the mechanism at the automatic switchboard to be controlled from the manual switchboard and for subsequently shunting the condensers to permit the passage of ringing current, a holding bridge across said trunk line on the automatic-switchboard side of said condensers, the said condenser shunting means being rendered effective upon a cessation of the current flow in said holding bridge, an alternative switch-holding circuit path, and means revertively controlled from the automatic switchboard after the connection has been set up and before the ringing current has been transmitted for preparing said alternative switch holding path so that it is completed when the holding bridge is opened to permit the condensers to be shunted for the passage of ringing current. 140
8. In a telephone system, a trunk line extending from a manual switchboard to an automatic switchboard, a switch-holding bridge across said trunk line at the manual switchboard end, a polarized relay included in said bridge, and a switch-holding circuit path alternative to said bridge and controlled by said relay. 150
9. In a telephone system, a trunk line ex-

tending from a manual switchboard to an automatic switchboard whereat a current flow in a given direction is brought about over said trunk line while a connection is being set up through the automatic switchboard and a reversed current flow is caused to take place after the connection is set up and before and after conversation, and whereat the current flow over the trunk line is prevented during conversation, a bridge across said trunk line at the manual switchboard end thereof including a polarized and a non-polarized relay, a supervisory lamp, and a circuit for said lamp controlled by said relays jointly.

10 15 20 25 30 35 40 45 50 55 60 65 70 75 80 85 90 95 100 105 110 115 120 125 130

10. In a combined manual and automatic telephone system in which automatic switches may be operated from a manual switchboard, a link circuit at said manual switchboard comprising two sections, a calling device for controlling the operation of automatic switches, said calling device having a normal position, and means responsive to the movement of said calling device from its normal position to effect the control of said switches for associating said calling device with one section of said link circuit to the exclusion of the other and for cancelling such association upon the return of the calling device to normal.

11. In a combined manual and automatic telephone system in which automatic switches may be operated from a manual switchboard, a link circuit at said manual switchboard comprising two sections, a calling device for controlling the operation of automatic switches, said calling device having a normal position, and means responsive to the movement of said calling device from its normal position to effect the control of said switches for associating said calling device with either predetermined section of said link circuit.

12. In a telephone system, an operator's link circuit comprising two sections, a calling device for controlling the operation of automatic switches over either section of said link circuit, a key contact for predetermining the association of said calling device with either of said sections, and means effective upon the turning of the calling device off-normal for completing the predetermined association.

13. In a telephone system, an operator's link circuit comprising two sections, a calling device for association with either section, operator controlled means for predetermining with which section the calling device shall be associated to the exclusion of the other and means effective upon the manipulation of said calling device by the operator for carrying into effect the predetermined operation.

14. In a telephone system, an operator's link circuit divided into three sections, a calling device connected to the middle section, a relay associated with the first section for dis-

connecting the first section from the middle section to permit the calling device to operate over the middle and third sections, a second relay similarly associated with the first section, coin-control apparatus, and means for operating either of said relays selectively when said coin controlled apparatus is being used and when said calling device is being used.

15. In a telephone system, an operator's link circuit divided into three sections, a relay for disconnecting the middle section from the first section, a similar relay for disconnecting the middle section from the third section, a calling device connected to the middle section, means for operating either of said relays when the calling device is in use, and means for operating either of said relays selectively when said calling device is not in use.

16. In a telephone system in which connections are set up through link circuits at a manual switchboard, a separate timing device for each link circuit, and operator-controlled means common to all link circuits for starting any desired timing device.

17. In a telephone system, a trunk line extending from a manual switchboard, a bridge across said trunk line at the manual switchboard including a polarized relay and a non-polarized relay, a supervisory device, and a circuit for said device controlled by said relays jointly.

18. In a telephone system, a trunk line extending from a manual switchboard, a bridge across said trunk line at the manual switchboard including a polarized relay and a non-polarized relay, a supervisory device, contacts on each relay, and a circuit for said device including said contacts in series.

19. In a telephone system in which connections are set up through link circuits at a manual switchboard, a separate timing device for each link circuit, a starting device common to all said timing devices, means for associating said starting device with any one of said timing devices, and means responsive to a subsequent operation of the starting device for starting the associated timing device.

20. In a telephone system in which connections are set up through link circuits at a manual switchboard a separate timing device for each link circuit, a talking key for each link circuit operable under the control of the operator at the switchboard, a starting device common to all said timing devices, and means responsive to an operation of said starting device for starting the operation of the timing device associated with any link circuit at which the talking key is operated.

21. In a telephone system, a link circuit comprising two sections, a calling device normally connected to both sections, means for selecting either section, and means automatically responsive to an operation of the

calling device for disconnecting the calling device from the other section.

22. In a telephone system, a link circuit comprising two sections, a calling device normally associated with both sections, means for selecting either section, and means automatically responsive to an operation of the calling device for disassociating the calling device from the other section.

23. In a telephone system a plurality of individual link circuits each comprising two sections, a common link circuit comprising two sections and containing a calling device arranged to exercise a control over switching apparatus by way of either section of any individual link circuit, means for connecting the sections of said common link circuit to the sections, respectively, of any individual link circuit and for selecting either section of the common link circuit, and means automatically responsive to an operation of said calling device to exercise a control over switching apparatus by way of the selected section of the common link and the connected section of the individual link for disassociating said calling device from the other section of the common link and connected section of the individual link.

In witness whereof, I hereunto subscribe my name this 24th day of September, A. D. 1927.

THOMAS F. CROCKER.
